FLOOR BEAM

John O. Bowser, New Kensington, Pa., assignor to
Aluminum Company of America, Pittsburgh, Pa.

Filed Dec. 11, 1972, Ser. No. 314,118

Term of patent 14 years

Int. Cl. D25—01

U.S. Cl. D13—1 J

FIG. 1.

FIG. 3.

FIG. 2.

FIG. 1 is a partial top plan view of said floor beam exhibiting the said design;

FIG. 2 is an end elevation view of the design illustrated in FIG. 1; and

FIG. 3 is a partial side elevation view of the design illustrated in FIG. 1.

I claim:

The ornamental design for a floor beam, substantially as shown.
